UNITED STATES PATENT OFFICE.

PHILANDER H. STANDISH, OF CLEVELAND, OHIO.

APPARATUS FOR CARRYING AND HEATING CHAIN-LINK BLANKS, &c.

No. 884,427.

Specification of Letters Patent.

Patented April 14, 1908.

Application filed April 24, 1907. Serial No. 370,085.

To all whom it may concern:

Be it known that I, PHILANDER H. STANDISH, a citizen of the United States of America, residing at Cleveland, in the county of 5 Cuyahoga and State of Ohio, have invented certain new and useful Improvements in Apparatus for Carrying and Heating Chain-Link Blanks, &c.; and I hereby declare the following to be a full, clear, and exact description of the invention, such as will enable others skilled in the art to which it pertains to make and use the same.

This invention relates to improvements in apparatus for carrying and heating chain-link-blanks, ring-blanks and other blanks or articles preparatory to welding or otherwise operating on them.

The primary object of this invention is to improve the apparatus illustrated and described in United States Letters Patent No. 20 502,594 granted to me August 1, 1893, to the end of rendering the apparatus more simple and inexpensive and otherwise advantageous in construction and more convenient, accurate and reliable in operation.

Another object is to enable and facilitate accuracy in the relative adjustment of the blank-carrier and blank-heating means.

Another object is to render the blank-carrier capable of being shifted out of the way of the blank-heating means to avoid exposure of the blank-carrier to the heat of the blank-heating means when the blank-carrier is not being operated.

With these objects in view, and to the end of realizing other advantages hereinafter appearing, this invention consists in certain features of construction, and combinations of parts hereinafter described, pointed out 35 in the claims and illustrated in the accompanying drawings.

In the said drawings, Figure 1 is a top plan of apparatus embodying my invention. Fig. 2 is a side elevation of the same. Fig. 3 is a vertical section on line 3—3, Fig. 2, looking in the direction indicated by the arrow. Fig. 4 is a vertical section in detail on line 4—4, Fig. 1, looking in the direction indicated by the arrow. Fig. 5 is a horizontal section on line 5—5, Fig. 2, looking downwardly.

Referring to the drawings, A indicates the casing of the furnace which is rendered stationary in any approved manner, being preferably mounted on and secured to standards 50 a which (see Figs. 2 and 3) are provided at

their lower ends with laterally projecting flanges a' into and through which are screwed set-screws e which rest upon a base or foundation f and render the furnace or heating means adjustable vertically, and nuts e' are mounted on the screws e to lock the set-screws in the desired adjustment.

B indicates the combustion or heating chamber of the furnace, which chamber is arranged centrally of the casing A, as shown in Figs. 1 and 3.

C represents an air-pipe or flue that discharges into the chamber B through an aperture b formed in one of the end walls of the said chamber, as shown in dotted lines Fig. 1.

D (see Fig. 1) represents a pipe arranged to conduct gas, oil, or other fluid used as fuel, to the chamber B. The pipe D is arranged centrally of the air-flue C and discharges within and centrally of the aperture b and such a distance from the discharging end of the said aperture that the gas or substitute and the air will commingle before being discharged into the chamber B of the furnace.

G represents a shaft which is arranged vertically externally and at one side of and a suitable distance from the furnace centrally between the ends of the furnace. The shaft G forms a portion and is arranged centrally of the carrier employed in conveying the blanks or articles to be heated through the heating chamber B of the furnace, and the said chamber is arranged concentrically of the said shaft and consequently concentrically of the blank-carrier, and the combustible mixture which constitutes the fuel to be discharged and burned within the said chamber is introduced into the chamber through the aperture b as already indicated.

The heating chamber B extends to the top surface of the furnace but the upper portion B' of the said chamber (see Figs. 1 and 3) is narrower than the central and lower portions of the chamber so as to concentrate the heat at the point where the blanks or articles to be heated are suspended and to prevent the heat from blowing or shooting upwardly out of the furnace. It will be observed therefore that the blanks or articles to be heated are suspended and heated during the operation of the apparatus within the upper and narrower portion B' of the chamber B and preferably the said upper and narrower portion of the said chamber is just wide enough to freely accommodate the suspension therein of the blanks or articles to be heated.

The shaft G is supported as will hereinafter appear, and the blank-carrier also comprises a wheel H which is operatively mounted on the upper portion of the shaft a suitable distance above the furnace. The wheel H has a circumferentially extending annular rim h and is provided with blank-holders I by which the blanks or articles to be heated are suspended within the upper portion B' of the heating chamber B. Preferably the rim h is provided in its upper side with grooves or recesses h' equidistantly spaced circumferentially of the wheel H and arranged radially of the said wheel, and each blank-holder I preferably consists of a bar or rod which has a horizontally arranged inner end-portion 7 engaging a recess h'. The inner end-portions 7 of the blank-holders I extend through the recesses h' and are consequently arranged 15 radially of the wheel H. The blank-holders I are detachably secured to the rim h as will hereinafter appear. It will be observed therefore that the blank-holders I are supported from and arranged radially relative 20 to the shaft G and spaced equidistantly circumferentially of the said shaft. Each blank-holder I extends laterally and outwardly and downwardly from the wheel-rim h and terminates at its outer and lower 25 end in a hook 8 adapted to receive a blank or article to be carried through the upper portion B' of the heating chamber B and suspended and heated within the said portion of the said chamber.

30 The means for detachably securing the blank-holders I to the wheel-rim h preferably comprise clamping plates or members J which rest upon the inner end-portions 7 of the blank-holders and are secured to the said wheel-rim by suitably applied screws J'. Obviously the side walls of the recesses h' are 35 instrumental in preventing displacement of the blank-holders I circumferentially of the blank-carrier.

40 The arrangement of the heating chamber of the furnace and the blank-carrier which, as already indicated, comprises the shaft G, wheel H, holders I, and the means for securing the said holders in place upon the wheel, is such that a blank hung upon the outer and hook-forming end of a holder I externally of the furnace is during the rotation of the carrier, when the latter is in its normal and operative position as shown, conveyed into 45 and through the upper portion B' of the heating chamber of the furnace so as to be properly heated in its passage through the said chamber. In Fig. 3 a chain-link-blank u is shown depending from a blank-holder I into the said upper portion B' of the said chamber.

50 The blank-carrier is intermittently actuated as will hereinafter appear, and the end walls of the upper portion B' of the heating chamber are recessed in the top thereof, as at

b' Figs. 1 and 2, to accommodate the passage or travel of a laden blank-holder I into and out of the chamber.

The inner horizontally arranged end-portions 7 of the blank-holders I project a suitable distance beyond the external peripheral surface of the wheel-rim h and operate as the teeth of a ratchet-wheel, being preferably cylindrical in cross section, as shown in Fig. 4, or at least rounded on top to facilitate the operative engagement therewith by a suitably applied and suitably operated pawl P which is preferably rigid with one end of a rod or pitman p which is suitably pivoted at its other end, as at p', to the crank t of a suitably supported crank-shaft T which is operatively provided with a suitably driven pulley or driving wheel T' which during the operation of the apparatus is rotated in the direction indicated by the arrow placed thereon in Fig. 2. An arm x is shown turnably embracing the shaft G and resting upon the hub of the wheel H. The arm x extends laterally from the shaft G to the pawl P which is connected with the said arm by a universal joint, as, for instance, by a ball-and-socket joint having its ball x' formed on the outer end of the arm and engaging a correspondingly shaped socket formed in the pawl which is made in halves or sections to accommodate the provision of the said joint, which sections are detachably secured together by suitably applied screws P'.

A collar y embracing and fixed to the shaft G above the pawl-connecting arm x prevents upward displacement of the said arm.

The shaft G has lateral bearing in two vertically arranged boxes 10 and 10 which are spaced vertically and formed on and being portions of a bracket K which is hinged or pivoted vertically, as at K', to lugs A' formed on the furnace-casing A at the adjacent end of the furnace. It will be observed therefore that the bracket K is capable of being swung laterally in a horizontal plane and away from the furnace-casing when the blank-carrier is elevated to the extent required to raise the blank-holders I out of and above the furnace, but the bracket is normally locked in its normal position by means comprising a bolt R, nuts R' and R² and a horizontally arranged arm 12 projecting from and formed on the bracket K. The bolt R is arranged horizontally and extends loosely through the bracket-arm 12, being pivoted vertically at one end, as at r (see Figs. 3 and 5) to a lug A² formed on the furnace-casing, and the nuts R' and R² are mounted on the said bolt at opposite sides respectively of the said arm.

A collar G' is mounted on and fixed to the lower end of the shaft G a suitable distance below the bracket K, which collar is borne by a lever M which surrounds the said collar and is provided with a slot M' large enough in

dimensions to accommodate the location of the said collar without interfering with the operation of the lever, and the slotted collar-surrounding portion of the lever is pivoted 5 horizontally at the sides of the lever to the collar by suitably applied pivot-forming screws O. The lever M is fulcrumed horizontally at one end, as at m, (see Fig. 2) to a bar or link L which is pivoted at its upper 10 end as at l, to the lower portion of the bracket. The lever M extends under the arm 12 of the bracket K. The last-mentioned pivot, the pivots O and the fulcrum m are parallel. It will be observed therefore 15 that the lever M is capable of being swung in a vertical plane, and that the shaft G of the blank-carrier, being borne by the lever, is raised or lowered according as the lever is swung upwardly or downwardly. In the 20 normal and operative position of the blank-carrier as shown the shaft-bearing lever M is of course in its downwardly swung position, and means for limiting the downwardly swinging of the lever are provided and com- 25 prise an upright bolt Q pivoted at its lower end, as at Q', to the lever parallelly with the fulcrum of the lever and between the shaft and the free end of the lever. The bolt Q extends from the lever M upwardly loosely 30 through the bracket-arm 12, and a thumb-nut Q² is mounted on the said bolt above the said arm, which thumb-nut forms a stop for limiting downward movement of the lever without interfering with the capability of the 35 lever to be swung upwardly. It will be observed that the blank-carrier is adjusted vertically by manipulating the thumb-nut Q².

Obviously upon tightening the nuts R' and R² the bracket K is locked to the furnace-casing, and consequently accidental lateral displacement of the said bracket is positively avoided. Withdrawal of the outer nut R², which is preferably in the form of a thumb-nut, obviously renders the bracket K free to 45 be swung laterally and outwardly when the blank-carrier is elevated to the extent required to raise the blank-holder I above the furnace.

I would here remark that to avoid heating 50 of the hook-forming ends of the blank-holders I during the heating of the furnace preparatory to the heating of blanks in the furnace or at other times during the operation of the furnace the blank-carrier is elevated 55 out of an operative position to remove the blank-holders upwardly from the heating chamber of the furnace, and then by withdrawing the thumb-nut R² the blank-carrier is swung laterally away from the furnace 60 after of course disengaging the pawl P from the engaging blank-holder.

It is of course obvious that in the operative position of the blank-carrier the vertical adjustment of the blank-holders I relative to 65 the heating chamber of the furnace is ef-

fected by the manipulation of the thumb-nut Q², and that the blank-carrier and consequently the blank-holders of the blank-carrier are properly adjusted laterally of the heating chamber of the furnace by manipulating the thumb-nut R² and nut R'. 70

By the construction and arrangement of parts hereinbefore described it will be observed that the heating chamber B has its upper portion B' open at the ends through 75 the medium of the slots b' in the end walls of the said chamber to accommodate the passage of the blanks through the said portion of the said chamber; that the blank-carrier is normally free to be elevated; that the bracket R constitutes a laterally movable support bearing the blank-carrier and arranged as required to render it capable of shifting laterally away from the blank-heating means so that obviously the blank-carrier, when it is elevated out of its operative 80 position to raise the blank-holders above the blank-heating means when rendered free to be thus shifted; that the bracket-arm 12 and bolt R and nuts R' and R² constitute 85 means for locking the said laterally adjustable support against displacement laterally in the normal and operative position of the blank-carrier so that the blank-carrier is secured in the desired lateral adjustment relative to the blank-heating means in the normal and operative position of the blank-carrier; that the blank-carrier-raising means formed by the lever M is borne by the said laterally movable support; that the bolt Q, 90 bracket-arm 12 and nut Q² constitute means for adjusting the lever and consequently the blank-carrier vertically, and that the said adjusting means is borne by the said laterally movable support. 95

What I claim is:—

1. In combination, a vertically shiftable blank-carrier comprising blank-holders for receiving and carrying the blanks to be heated; blank-heating means arranged to heat the blanks carried by the blank-carrier in the normal and operative position of the blank-carrier; means for actuating the blank carrier; means for raising the blank-carrier out of its operative position, and a laterally movable support bearing the blank-carrier. 110

2. In combination, a blank-carrier shiftable up and down and comprising blank-holders for receiving and carrying the blanks to be heated; blank-heating means arranged to heat blanks carried by the blank-carrier in the operative position of the blank-carrier; means for raising the blank-carrier out of its operative position, and a laterally movable support bearing the blank-carrier. 120

3. In combination, a blank-carrier shiftable up and down and comprising blank-holders for receiving and carrying the blanks to be heated; blank-heating means arranged to heat blanks carried by the blank-carrier 125

in the operative position of the blank-carrier; means for raising the blank-carrier out of its operative position; a laterally movable support bearing the blank-carrier, and means for locking the blank-carrier against displacement laterally relative to the heating means in the operative position of the blank-carrier.

4. In combination, a vertically shiftable and laterally shiftable blank-carrier and comprising blank-holders for receiving and carrying the blanks to be heated; blank-heating means arranged to heat the blanks carried by the blank-carrier in the normal and operative position of the blank-carrier; means for actuating the blank-carrier, and means for locking the blank-carrier against displacement laterally relative to the blank-heating means in the normal and operative position of the blank-carrier.

5. In combination, a vertically shiftable and laterally shiftable rotary blank-carrier comprising blank-holders suitably spaced from and circumferentially of the axis of the blank-carrier; blank-heating means arranged at one side of the axis of the carrier and in position to heat the blanks carried by the blank-carrier; means for actuating the blank-carrier, and means for locking the blank-carrier against displacement laterally relative to the blank-heating means in the normal and operative position of the blank-carrier.

6. In combination, a rotary blank-carrier shiftable laterally as well as up and down and comprising blank-holders for receiving and carrying the blanks to be heated, and blank-heating means arranged to heat blanks carried by the blank-carrier in the operative position of the blank-carrier.

7. In combination, a vertically shiftable rotary blank-carrier comprising blank-holders suitably spaced from and circumferentially of the axis of the blank-carrier; blank-heating means arranged at one side of the axis of the carrier and in position to heat the blanks carried by the blank-carrier; means for actuating the blank-carrier; a laterally movable support for the blank-carrier; and means for locking the said support against displacement laterally in the normal and operative position of the blank-carrier.

8. In combination, a vertically shiftable rotary blank-carrier comprising blank-holders suitably spaced from and circumferentially of the axis of the blank-carrier; blank-heating means arranged at one side of the axis of the blank-carrier; means for actuating the blank-carrier; a pivotally supported bracket supporting the blank-carrier and arranged as required to render it capable of being swung laterally away from the blank-heating means.

9. In combination, a vertically shiftable and laterally shiftable rotary blank-carrier comprising blank-holders suitably spaced from and circumferentially of the axis of the blank-carrier; a furnace having a heating

chamber arranged concentrically relative to the blank-carrier and in position to receive the blanks carried by the blank-carrier in the normal and operative position of the latter, which heating chamber has its upper portion open at the ends to accommodate the passage of the blanks through the said portion of the said chamber, and means for actuating the carrier.

10. In combination, a vertically shiftable blank-carrier comprising blank-holders for carrying the blanks to be heated; a furnace having a heating chamber arranged to receive the blanks carried by the blank-carrier in the operative position of the latter and open at the top of the furnace; means for raising and lowering the blank-carrier, and a laterally movable support for the means instrumental in raising and lowering the blank-carrier.

11. In combination, a vertically shiftable blank-carrier comprising blank-holders for carrying the blanks to be heated; a furnace having a heating chamber arranged to receive the blanks carried by the blank-carrier in the operative position of the latter and open at the top of the furnace; means for raising and lowering the blank-carrier; a laterally movable support for the means instrumental in raising and lowering the blank-carrier, and means for locking the said support against lateral displacement.

12. In combination, a shiftable blank-carrier comprising blank-holders for carrying the blanks to be heated; a furnace having a heating chamber arranged to receive the blanks carried by the blank-carrier in the operative position of the latter; means for shifting the blank-carrier to move blank-holders into and out of the chamber, and means whereby the blank-carrier is shiftable away from the chamber when the blank-carrier is in position with the said blank-holders externally of the chamber.

13. In combination, a vertically shiftable rotary blank-carrier comprising blank-holders suitably spaced circumferentially of the blank-carrier; a furnace having a heating chamber arranged concentrically relative to the blank-carrier and in position to receive the blanks carried by the blank-carrier in the normal and operative position of the latter, which heating chamber has its upper portion open at the ends to accommodate the passage of the blanks through the said portion of the said chamber; means for actuating the carrier; means for raising the blank-carrier out of its normal and operative position, and a laterally movable support for the blank-carrier-raising-means.

14. In combination, a vertically shiftable rotary blank-carrier comprising blank-holders suitably spaced circumferentially of the blank-carrier; a furnace having a heating chamber arranged concentrically relative to

- the blank-carrier and in position to receive the blanks carried by the blank-carrier in the normal and operative position of the latter, which heating chamber has its upper portion open at the ends to accommodate the passage of the blanks through the said portion of the said chamber; means for actuating the carrier; means for raising the blank-carrier out of its normal and operative position; a laterally movable support for the blank-carrier-raising means, and means for locking the said support against lateral displacement in the normal and operative position of the blank-carrier. 5 70
15. In combination, a rotary blank-carrier shiftable up and down and supported as required to render it capable of being swung laterally and comprising blank-holders for carrying the blanks to be heated; a furnace having a heating chamber arranged to receive blanks carried by the blank-carrier in the operative position of the latter, and means for operating the blank-carrier. 10 75
20. In combination, a blank-carrier adjustable up and down and comprising blank-holders for carrying blanks to be heated; a furnace having a heating chamber arranged to receive blanks carried by the blank-carrier in the operative position of the latter; means for operating the blank-carrier; means for adjusting the blank-carrier vertically, and a laterally adjustable support bearing the said adjusting means and the blank-carrier. 15 80
21. In combination, a blank-carrier adjustable up and down and comprising blank-holders for carrying blanks to be heated; a furnace having a heating chamber arranged to receive blanks carried by the blank-carrier in the operative position of the latter; means for operating the blank-carrier; means for adjusting the blank-carrier vertically; a laterally adjustable support bearing the said adjusting means and blank-carrier, and means for locking the said support against displacement laterally in the desired adjustment of the said support. 25 85
22. In combination, a vertically shiftable rotary blank-carrier comprising blank-holders suitably spaced circumferentially of the blank-carrier; a furnace having a heating chamber arranged concentrically relative to the blank-carrier and in position to receive the blanks carried by the blank-carrier in the normal and operative position of the latter, which heating chamber has its upper portion open at the ends to accommodate the passage of the blanks through the said portion of the said chamber; means for actuating the blank-carrier; a laterally adjustable support bearing the blank-carrier, and means for securing the blank-carrier in the desired lateral adjustment. 30 90
35. In combination, a vertically shiftable rotary blank-carrier comprising blank-holders suitably spaced circumferentially of the blank-carrier; a furnace having a heating chamber arranged concentrically relative to the blank-carrier and in position to receive the blanks carried by the blank-carrier in the normal and operative position of the latter, which heating chamber has its upper portion open at the ends to accommodate the passage of the blanks through the said portion of the said chamber; means for actuating the blank-carrier; a laterally adjustable support bearing the blank-carrier, and means for securing the blank-carrier in the desired lateral adjustment. 40 95
45. In combination, a vertically shiftable rotary blank-carrier comprising blank-holders suitably spaced circumferentially of the blank-carrier; means for heating the blanks carried by the blank-carrier in the normal and operative position of the latter; means for actuating the blank-carrier; means for raising the blank-carrier above the blank-heating means; a laterally adjustable movable support carrying the blank-carrier-raising means, and means for securing the said support in the desired adjustment. 50 100
55. In combination, an adjustable blank-carrier comprising blank-holders for carrying the blanks to be heated; means for heating the blanks carried by the blank-carrier in the operative position of the latter; means for operating the blank-carrier; means for adjusting the blank-carrier, and a movable support bearing the said adjusting means and the blank-carrier. 60 105
65. In combination, a vertically adjustable rotary blank-carrier comprising blank-holders suitably spaced circumferentially of the blank-carrier; means for heating the blanks carried by the blank-carrier in the normal and operative position of the latter, which heating chamber has its upper portion open at the ends to accommodate the passage of the blanks through the said portion of the said chamber; means for actuating the blank-carrier; means for adjusting the blank-carrier vertically; a laterally adjustable support bearing the said adjusting means and the blank-carrier, and means for locking the said support against displacement laterally in the desired adjustment of the said support. 70 110
75. In combination, a rotary blank-carrier comprising a vertically shiftable upright shaft and blank-holders supported from the 75 115

upper end and suitably spaced around the shaft; a furnace having a heating chamber whose upper portion is arranged concentrically relative to the blank-carrier and in position to receive the blanks carried by the blank-carrier in the normal and operative position of the latter and open at the ends to accommodate the passage of the blanks through the said portion of the said chamber; 5 a pivotally supported bracket affording lateral bearing to the shaft and arranged as required to render it capable of adjusting the blank-carrier laterally relative to the aforesaid portion of the heating chamber; means for locking the bracket in the desired lateral adjustment of the blank-carrier, a lever bearing the shaft and supported from the bracket, which lever is applied as required to render it capable of movement to raise the shaft.

10 25. In combination, a rotary blank-carrier comprising a vertically shiftable upright shaft and blank-holders supported from the upper end and suitably spaced around the shaft; a furnace having a heating chamber whose upper portion is arranged concentrically relative to the blank-carrier and in position to receive the blanks carried by the blank-carrier in the operative position of the latter and open at the ends; a pivotally supported bracket affording lateral bearing to the shaft and arranged to swing in a vertical plane; another bracket pivotally supported from the furnace and arranged to swing in a horizontal plane; a bolt extending loosely through the last-mentioned bracket; two nuts mounted on the bolt at opposite sides respectively of the bolt-penetrated portion of the last-mentioned bracket, and a shaft-raising lever bearing the shaft.

15 30 35 40 45 50 55 60 65 70 75 80 85 90 95 100 105 110 115 26. In combination, a rotary blank-carrier comprising a vertically shiftable upright shaft and blank-holders supported from the upper end and suitably spaced around the shaft; a furnace having a heating chamber whose upper portion is arranged concentrically relative to the blank-carrier and in position to receive the blanks carried by the blank-carrier in the operative position of the latter and open at the ends; a pivotally supported bracket affording lateral bearing to the shaft and having a projecting arm; a lever for shifting the shaft vertically, which lever bears the shaft and is supported from the bracket, and extends under the aforesaid bracket-arm; a bolt pivotally attached to the lever and extending from the lever loosely through the said arm, and a nut on the bolt and resting on the arm.

27. In combination, a rotary blank-carrier comprising a vertically shiftable upright shaft and blank-holders supported from the upper end and suitably spaced around the

shaft; means for heating the blanks carried by the blank-holders of the blank-carrier; a suitably supported bracket affording lateral bearing to the shaft and provided with a projecting arm; a link pivoted horizontally to and depending from the bracket; a lever fulcrumed to the link and arranged with its axis parallel with the axis of the link, which lever bears the shaft; an upright bolt extending loosely through the aforesaid arm and pivotally attached to the lever, and a nut on the bolt and resting on the said arm.

28. The combination, with blank-heating means, of a suitably supported upright shaft at one side of the blank-heating means; a wheel operatively mounted on the upper portion of the shaft and having a circumferentially extending rim; blank-holders borne by the said rim and projecting laterally and outwardly and downwardly beyond the outer peripheral surface of the rim and terminating at their outer and lower ends in members arranged to receive and expose blanks carried thereby to the blank-heating means during the rotation of the shaft; a laterally projecting arm loosely embracing the shaft above the wheel; a suitably operated pawl arranged at the outer end of the said arm in position to operatively engage a blank-holder, and a universal joint between the pawl and the arm.

29. The combination, with blank-heating means, of a blank-carrier comprising a suitably supported vertically arranged shaft at one side of the blank-heating means and blank-holders supported from and suitably spaced around the upper portion of the shaft, which blank-holders have radially arranged portions rounded on top, and a suitably supported and suitably operated pawl arranged to operatively engage the radially arranged portion of a blank-holder.

30. The combination, with blank-heating means, of a blank-carrier comprising a suitably supported upright shaft arranged at one side of the blank-heating means and blank-holders supported from and equidistantly spaced around the shaft, which blank-holders are arranged to expose the blanks carried thereby to the blank-heating means during the operation of the apparatus, and a suitably supported and suitably operated pawl arranged to operatively engage a blank-holder and intermittently rotate the blank-carrier.

In testimony whereof, I sign the foregoing specification, in the presence of two witnesses.

PHILANDER H. STANDISH.
